UNITED STATES PATENT OFFICE

152,890

DESIGN FOR A TWO-HANDED SAW HANDLE

Thomas Lamb, New York, N. Y.

Application May 26, 1948, Serial No. 146,610

Term of patent 14 years

(Cl. D93—4)

To all whom it may concern:

Be it known that I, Thomas Lamb, a citizen of the United States, residing at 15 East 48th Street, in the county and State of New York, have invented a new, original, and ornamental Design for a Two-Handed Saw Handle, of which the following is a specification, reference being had to the accompanying drawing, forming part thereof.

Figure 1 is a top plan view of a two-handed saw handle, showing my new design.

Figure 2 is a front elevation, and

Figure 3 is a rear elevation.

I claim:
The ornamental design for a two-handed saw handle, as shown.

THOMAS LAMB.
